William U. Hohwieler, Morrisville, Pa.

Application July 25, 1946, Serial No. 131,904

Term of patent 14 years

(Cl. D71—1)

To all whom it may concern:

Be it known that I, William U. Hohwieler, a citizen of the United States, residing at Morrisville, in the county of Bucks, State of Pennsylvania, have invented a new, original, and ornamental Design for a Dummy for Testing Parachutes, of which the following is a specification, reference being made to the accompanying figures of the drawing, forming a part thereof.

Fig. 1 is a side view;

Fig. 2 is a top view; and

Fig. 3 is a front view of a dummy for testing parachutes embodying my design.

I claim:

The ornamental design for a dummy for testing parachutes, substantially as shown.

WILLIAM U. HOHWIELER.
